(73) Assignee: Alfa Technology Limited (HK)

Primary Examiner—Nanda Bondade
(74) Attorney, Agent, or Firm—Strasburger & Price L.L.P.;
Paul W. Fulbright

(**) Term: 14 Years

(57) CLAIM

The ornamental design for a combined radio, cassette tape recorder and compact disc player, as shown and described.

DESCRIPTION

Nov. 12, 1999 (HK) 9911537

(51) LOC (7) Cl. 14-01

FIG. 1 is a top view of the claimed invention.

(52) U.S. Cl. D14/168

FIG. 2 is a front view of the claimed invention; and,

**(58) Field of Search D14/156, 160-165,
D14/167-168, 188, 193-198; D21/516;
455/344, 347-351**

FIG. 3 is a side view of the claimed invention.

(56) References Cited

The bottom and back views of the claimed invention are unornamented.
